UNITED STATES PATENT OFFICE.

WILLIAM A. SCHRAUBSTADTER, OF ST. LOUIS, MISSOURI.

DESIGN FOR A FONT OF TYPE.

41,336.

Specification for Design.

Patented Apr. 25, 1911.

Application filed January 31, 1910. Serial No. 541,207. Term of patent 7 years.

To all whom it may concern:

Be it known that I, WILLIAM A. SCHRAUBSTADTER, a citizen of the United States, and a resident of the city of St. Louis and State of Missouri, have invented a new, original, and ornamental Design for a Font of Type, of which the following is a specification.

My design consists in the features shown in the accompanying drawing which forms part of this specification.

I claim:

The ornamental design for a font of type as shown.

WM. A. SCHRAUBSTADTER.

In the presence of—

A. G. BLANNER,
HENRY ROEDER.

Copies of this patent may be obtained for five cents each, by addressing the "Commissioner of Patents, Washington, D. C."
